UNITED STATES PATENT OFFICE.

ROBERT G. HENRY, OF WATERBURY, CONNECTICUT.

BLANKET OR SIMILAR ARTICLE.

SPECIFICATION forming part of Letters Patent No. 351,031, dated October 19, 1886.

Application filed June 23, 1886. Serial No. 205,966. (No model.)

To all whom it may concern:

Be it known that I, ROBERT G. HENRY, a citizen of the United States, residing at Waterbury, in the county of New Haven and State of Connecticut, have invented certain new and useful Improvements in Devices for Folding and Hanging Blankets; and I do hereby declare the following to be a full, clear, and exact description of the invention, such as will enable others skilled in the art to which it appertains to make and use the same.

My invention has for its object to produce means for readily folding and hanging blankets and similar articles.

With this end in view I have devised the novel construction and arrangement of which the following description, in connection with the accompanying drawings, is a specification.

Figure 1 is a plan view of a blanket or similar article embodying my invention; Fig. 2, an elevation showing the article folded once; Fig. 3, an elevation showing it folded twice; Fig. 4, an elevation showing it folded three times, and Fig. 5 a detail view illustrating an other form of holding device.

1 indicates the article, and 2 rings, loops, straps, or other holding devices, a series of which are secured to the article midway between opposite sides or ends. The number 30 of these rings or holding devices is not of the essence of my invention, although three is the number that I ordinarily use, being amply sufficient for all ordinary articles. Two of these rings or holding devices are attached near 35 the opposite edges, as clearly shown, and the other one about midway between them.

In order to illustrate the principle of my invention more clearly, I have shown the holding devices of a much larger size relative 40 ly to the article than would ordinarily be used. These holding devices may be made of any ordinary material—as, for example, metal, wood, leather, or a suitable composition—and they may be attached to the article in 45 any suitable manner. In the present instance I have shown rings held by loops 3, which are secured in place upon the blanket or other article by disks 4, of leather, stitched to the article. Straps, however, may be riveted directly to the article, if preferred, as 50 shown in Fig. 5. Suppose that it is desired to take a blanket from a horse and fold it, or to fold any similar article, one of the outside holding devices is caught in one hand and

the other outside holding device in the other 55 hand. Upon lifting up the blanket the folds drop into the position shown in Fig. 2. The second fold is made by taking the two outside holding devices in one hand and the middle holding device in the other hand, the 60 position of the article after this operation being clearly shown in Fig. 3. Should it be desired to give the article still another fold, the holding devices are all taken in one hand. This will give the article three folds, the po- 65 sition after folding being clearly indicated in Fig. 4, the three holding devices being at this time in line with each other. The article may now be readily hung up by catching the three rings or holding devices over a nail or 70 peg.

I have found my invention in practice to be of especial value as applied to horse-blankets, both in traveling and in the barn. By the use of this invention a blanket may be folded 75 in the night as well as by daylight, in a fraction of the time ordinarily required, and much more neatly and compactly. In connection with stable-blankets, it is, if possible, still more valuable. It is of course well known that the 80 stable-blanket is an article that rarely has a place of its own. It may be folded up or hung up, but rarely either. It is of course inconvenient to provide shelves for the several blankets used by horses in a row of stalls. The blankets are therefore frequently thrown into the 85 most convenient corner. My present invention, however, enables a blanket to be readily and quickly folded as it is removed from the horse, and to be hung up entirely out of the way, 90 there being no danger of its dangling on the floor or falling down.

Having thus described my invention, I claim—

As an improved manufacture, a blanket or 95 similar article provided with two or more hanging devices arranged centrally thereof, two of the said devices being at or near the opposite edges of the said article, whereby the said hanging devices are adapted for use in 100 evenly folding as well as in suspending the article to which they are attached, substantially as set forth.

In testimony whereof I affix my signature in presence of two witnesses.

Witnesses: ROBERT G. HENRY.
D. H. MELOY,
ROBERT ROBINSON.
